UNITED STATES PATENT OFFICE.

EDUARD LEISSNER, OF NEW YORK, N. Y., ASSIGNOR TO LEISSNER & LOUIS,
OF SAME PLACE.

DESIGN FOR WALL-PAPER.

SPECIFICATION forming part of Design No. 11,987, dated October 26, 1880.

Application filed July 31, 1880. Term of patent 3½ years.

To all whom it may concern:

Be it known that I, EDUARD LEISSNER, of New York, in the county and State of New York, have invented a new and original Design for Wall-Paper, of which the following is a specification.

This invention relates to a new and original design for wall-paper and similar fabrics.

It consists in the novel grouping and configuration of figures hereinafter more fully described.

The accompanying photograph illustrates a face view of wall-paper having my new design.

The figure A is a vase-shaped ornament, whose lower portion is oval, and is ornamented with a figure, D, representing a human face, surrounded by radiating oval leaves, with the mouth and cheeks covered by leaf-like figures a a, and the forehead covered by a band, e. The upper portion of the vase A curves outward from the contracted middle, and a snake-like head, f, projects on each side from the lip of the vase. Upon the vase A is set a leafy stem, g, supporting a circular flower, h. Wing-like figures B B project one on each side of the figure A, and stalks C C, with leaves d d thereon, and flowers b b growing at the ends, curve around the figure A, starting from its base, one on each side. These figures A B C D a b d e f g h compose the group E.

The group G, adjoining E, is composed of a stem, H, standing on a flower-like ornament, i, which rests on three leaf-shaped supports, l l l. From near the base q of the stem H project on either side the oval fan-shaped ornaments m m. From behind this base q project the stalks n n, similar to the stalks d d, but bent downward, and the lily-shaped flowers O O, with projecting pistils, there being one stalk n n and one flower O on each side of the stem H. From the stem H run the two tendrils r r, one on each side, curving round the flowers O O, and on this stem stands the flower p, with widely-open petals, and containing numerous small pistils.

I claim—

1. The design for wall-paper, consisting of the vase-shaped figure A, with ornaments f f thereon, substantially as shown.

2. The design for wall-paper, consisting of

the sunflower-like figure D, substantially as shown.

3. The design for wall-paper, consisting of the figure A, with ornament D thereon, substantially as shown.

4. The design for wall-paper, consisting of the figures A D g b, substantially as shown.

5. The design for wall-paper, consisting of the figure D, leaves d, and flowers b, substantially as shown.

6. The design for wall-paper, consisting of the figures A B C D, substantially as shown.

7. The design for wall-paper, consisting of the figures A B C D g h, substantially as shown.

8. The design for wall-paper, consisting of the group E, composed of figures A B C D a b d e f g h, substantially as shown.

9. The design for wall-paper, consisting of the oval fan-like figures m and stem H, substantially as shown.

10. The design for wall-paper, consisting of the stem H, having lily-shaped figures O, with the projecting pistils, substantially as shown.

11. The design for wall-paper, consisting of the open flower-like figure p, substantially as shown.

12. The design for wall-paper, consisting of the stem H and curving bands r r, substantially as shown.

13. The design for wall-paper, consisting of the stem H, supported on leaf-shaped figures l l l and i, substantially as shown.

14. The design for wall-paper, consisting of the figures H l i m r, substantially as shown.

15. The design for wall-paper, consisting of the figures H l i m p, substantially as shown.

16. The design for wall-paper, consisting of the figures H l i m p r, substantially as shown.

17. The design for wall-paper, consisting of the figures H l i m n o p, substantially as shown.

18. The design for wall-paper, consisting of the group G, composed of figures H l i m n o p r, substantially as shown.

19. The design for wall-paper, consisting of the groups E and G, substantially as shown.

Witnesses: EDUARD LEISSNER.

RUDOLF KLEEMANN,
WILLY G. E. SCHULTZ.
